(57) **CLAIM**

The ornamental design for a paint container, as shown and described.

DESCRIPTION

FIG. 1 is a top, right side and back perspective view of a paint container;

FIG. 2 is a bottom, left side and back perspective view of the container of FIG. 1;

FIG. 3 is a left side view of the container of FIG. 1;

FIG. 4 is a right side view of the container of FIG. 1;

FIG. 5 is a back view of the container of FIG. 1;

FIG. 6 is a front view of the container of FIG. 1;

FIG. 7 is a top view of the container of FIG. 1; and,

FIG. 8 is a bottom view of the container of FIG. 1.

The dashed lines in the FIGS. are for illustrative purposes only and form no part of the claimed design.

The dot-dashed-dot lines in the FIGS. represent the border between claimed and unclaimed subject matter and form no part of the claimed design.

1 Claim, 8 Drawing Sheets
